US00D782779S

(12) **United States Design Patent** (10) **Patent No.:** **US D782,779 S**
(45) **Date of Patent:** **** Apr. 4, 2017**

(54) **DINOSAUR-SHAPED CRACKER**

(71) Applicant: **Plum, PBC**, Emeryville, CA (US)

(72) Inventor: **Rachel Jia Yeh Li**, San Rafael, CA (US)

(73) Assignee: **Plum, PBC**, Emeryville, CA (US)

(**) Term: **15 Years**

(21) Appl. No.: **29/563,820**

(22) Filed: **May 9, 2016**

(51) LOC (10) Cl. **01-01**

(52) U.S. Cl.

USPC **D1/128**; D1/107

(58) **Field of Classification Search**

USPC D1/100-130, 199; 426/5, 76, 87, 92, 94, 426/95, 99, 101, 103, 104, 108, 138-139, 426/143, 144, 279, 282, 283, 391, 514, 426/549, 559, 560, 660, 808; D21/606, D21/615; D25/138; D7/359; D6/597, D6/601, 595, 598; 119/710; D30/160; D24/195
